UNITED STATES PATENT OFFICE.

WILLIAM A. GIBSON, OF ALLENTOWN, PENNSYLVANIA, ASSIGNOR TO BRADLEY PULVERIZER COMPANY, OF ALLENTOWN, PENNSYLVANIA, A CORPORATION OF MAINE.

ADJUSTABLE PLOW FOR CENTRIFUGAL GRINDING MILLS.

Application filed December 29, 1924. Serial No. 758,835.

This invention relates to improvements in centrifugal grinding mills and the object thereof is to provide means for more effectively delivering the material to be ground to the co-operating grinding members.

Centrifugal mills of this type comprise a grinding pan having an annular die therein, usually a plurality of centrifugally operable grinding rolls co-operating with said 10 annular die and a plow or plows rotatable with said grinding roll or rolls and in advance thereof extending into the material to be ground and acting to deliver the material to the co-operating grinding members.

15 In grinding mill constructions of this type heretofore constructed the plows have been secured in a predetermined rigid position. It has been found that the plow acts differently upon different materials, such as those 20 having different specific gravity, or upon materials differing in fineness, and particularly with a very different action upon coarse material and relatively fine material which is frequently introduced into the mill for 25 repulverization.

The object of the present invention is broadly to provide means for adjustably supporting the plow to enable it to be secured in various different positions of adjustment.

One of the objects of the invention is to provide means for securing the plow at different distances toward and from the bottom of the pan.

35 Another object of the invention is to provide means for differing the inclination or tilt of the plow so that the face which serves to project the material toward the co-operating grinding members may be more or less 40 inclined.

A further object of the invention is to provide means for rotatably adjusting the plow about the axis of its support so that the position of the plow may be varied with 45 respect to the radius of the annular grinding die.

The present invention comprises means for accomplishing all of these purposes as well as easily operable means for securing 50 the various adjustments.

While the invention is applicable to numerous usual types of grinding mills, it is illustrated herein as embodied in a centrifugal grinding mill of the general type illustrated in Patent No. 1,175,436, Griffin, grant-

ed March 14, 1916, and No. 1,473,341, Gibson and Needham, granted November 6, 1923.

In the drawings:

Fig. 1 is a view, partially in vertical section, 60 of a centrifugal grinding mill of the type above described;

Fig. 2 is an enlarged detail front elevation of a plow-supporting arm and plow adjustably secured thereto embodying a preferred form of the invention, the plow-supporting arm being broken away;

Fig. 3 is a side elevation of the same; and,

Fig. 4 is a view showing the plow-supporting arm in transverse section and the plow and the means for securing the plow to said arm in elevation.

The grinding mill illustrated in the accompanying drawings comprises a base 1 having an upturned curb 2 forming a grinding pan to receive the material to be ground, a grinding ring or die 3 being detachably secured between the upper portion of the curb 2 and a clamping section 4 70 which is secured to the curb 2, the upper portion of the curb and clamping member 4 being provided with inclined faces complementary to peripheral inclined faces upon the grinding ring or die. The base 2 is 75 also provided with extensions or bosses 5 which receive the lower ends of preferably A-shaped standards 6 upon the upper ends of which are mounted saddles 7 which support a transverse girder 8 which sustains 80 the rotating parts of the mill.

The rotating members comprise a quill shaft 9 which is supported by a bevel gear 10 which rests upon the transverse girder 8 and is driven by a beveled pinion 11 upon a suitable driving shaft 12 journaled in bearings in the saddles 7. The quill shaft 9 is rotatably mounted upon a stationary central shaft 13 the lower end of which is tapered and suitably secured in a central boss 14 integral with and extending upwardly from the pan. The shaft 13 has secured to it a carrier 15 of general cylindrical form, the outer wall of which surrounds a stationary hopper 16 to which the material is supplied. The carrier is provided with a plurality of laterally extending arms 17 upon which rocker heads 18 are pivotally mounted and the shafts 19 of the centrifugally operated crushing rolls 20 which co-operate with the 100 105 110

annular die 3 are rotatably mounted in the rocker heads. The base portion of the carrier is provided with downwardly and outwardly extending chutes 21 which deliver the material in proximity to the periphery of the pan and into the path of the crushing rolls.

The lower end of the quill shaft supports a horizontally disposed spider 22 which is made in sections to fit around and enclose the reduced lower end of the quill shaft which is provided with a rib 23 adapted to engage an annular recess in the spider and prevent the latter from longitudinal movement upon the quill shaft. This spider serves to support the plow or plows which travel in the grinding chamber beneath the path of the rolls and force the material in the grinding pan into the path of the rolls.

The construction thus described may be and desirably is similar to that disclosed in the prior patents above referred to.

In previous constructions the plows have been rigidly supported upon arms which in turn have been rigidly secured to the spider upon the lower end of the quill shaft. The object of the present invention, as heretofore mentioned, is to provide means for adjustably supporting the plow in such a manner that it may be secured in any or all of the various positions of adjustment so that the most effective action of the plow may be obtained for the particular kind of material which is being treated in the mill. The adjustments provided for by the present invention comprise, first, the bodily adjustment of the plow toward and from the bottom of the pan; second, a tilting adjustment by means of which the angular position of the face of the blade relative to its plane of movement may be varied; and, third, an adjustment about the axis of the plow support by means of which the angular relation of the blade to the radius of the annular die may be varied.

Any suitable means may be provided for accomplishing any or all of these adjustments within the spirit and scope of the claims.

In the preferred embodiment of the invention illustrated herein the spider is provided with one or preferably a series of downwardly and outwardly extending sockets 24 which may be of cylindrical form and in which the upper ends 25 of cylindrical plow-supporting arms 26 are mounted and secured in any suitable manner as by set screws 27, or other suitable means which will permit the arm to be rotatably adjusted about its axis in such a manner that the plow may be adjusted angularly with respect to the radius of the annular die.

The plows may be secured to the lower ends of the arms 26 in any suitable manner to provide for other adjustments. In the

preferred construction illustrated the plow comprises a flat inclined blade 28 to engage the material and an integral upwardly extending preferably flat member or web 29 which is secured to the arm 26 by a bolt 30 and is provided at its upper end with a laterally extending arm 31 which extends behind and across the rear edge of the arm 26. A screw 32 seated in the arm 31 abuts against the rear edge of the arm and serves to retain the plow in adjusted position about the axis of the bolt 30 as the engagement of the plow with the material tends to rotate the plow about the axis of the bolt in a direction which will force the end of the screw 32 against the rear edge of the arm 26. Obviously by screwing up or unscrewing the screw 32 the plow may be tilted more or less relatively to the plane of its movement. By thus varying the angular position of the face of the plow the material may be projected upwardly at a greater or less angle.

It is desirable in treating different materials that the plow shall travel in paths at different distances from the bottom of the pan. This is accomplished by providing means by which the effective length of the plow-supporting arm may be varied. Means are provided in the present invention for producing this adjustment either separately or coincidentally with the tilting adjustment. This is accomplished by providing the arm 26, or the member or web 29 of the plow, but preferably the arm 26 with a plurality of arcuate ribs 33 and the co-operating member, preferably the member 29 of the plow with a complementary arcuate rib 34 which is concentric with the axis of the bolt 30 which extends in a direction substantially radial to the path of movement of the plow. The stem of the bolt 30 extends through and fits an aperture in the member 29 which is concentric with the rib 34, but is mounted in a slot 35 extending longitudinally of the arm 26.

By reason of this construction the plow may be adjusted longitudinally of the arm by unscrewing the nut of the bolt and raising or lowering the position of the rib 34 in such a manner that it will interengage with selected ribs upon the arm 26 and thereupon setting up the bolt 30. By reason of the fact that the rib 34 is concentric with the axis of the bolt and the ribs 33 are complementary in curvature to the rib 34 the tilting adjustment above described can be made at the same time by setting up or withdrawing the screw 32 the desired amount.

It will be apparent that by reason of the adjustments above described the plow can be raised or lowered relatively to the pan so that it will engage more or less of the material in the pan; the plow may be tilted to adjusted positions to cause the material to be projected upwardly to a greater or less

height and the plow may be adjusted about the axis of the arm 26 so that it will project the material outwardly in different angular relations to radii of the pan.

5. By reason of these adjustments the plow can be made more effectively to deliver the material to the co-operating grinding rolls and die and the efficiency of the grinding mill thereby greatly increased.

10. It will be understood that the embodiment of the invention disclosed herein is of an illustrative character and that various changes in design, construction and arrangement of parts may be made within the spirit and scope of the following claims.

Having thus described the invention, what is claimed as new, and desired to be secured by Letters Patent, is:

1. In a centrifugal grinding mill comprising a pan, an annular die, a centrifugally operable grinding member co-operating therewith and a plow movable with said grinding member, means for supporting said plow including adjustable means for securing said plow in different vertically tilted positions relatively to the plane of said pan about an axis substantially radial to the path of movement of the plow.

2. In a grinding mill comprising a pan, an annular die, a plurality of co-operating grinding members rotatable about a common central axis co-operating with said die, a plow-supporting arm rotatable about said central axis, a plow, interengaging members upon said plow and said arm and means pivotally connecting said plow to said arm operable to permit said plow to be secured in different vertically tilted positions relatively to the plane of said pan.

3. In a grinding mill comprising a pan, an annular die, a plurality of co-operating grinding members rotatable about a common central axis co-operating with said die, a plow-supporting arm rotatable about said central axis, a plow, complementary faces upon said plow and arm having interengaging members and pivotal means for clamping said plow to said arm operable to permit adjustment of said plow longitudinally of said arm and also rotatably about said pivotal connection.

4. In a grinding mill comprising a stationary grinding member and a plurality of co-operating grinding members rotatable about a common central axis, a plow-supporting member also rotatable about said central axis, a plow, complementary faces upon said plow and said arm, one of said

faces having a plurality of arcuate ribs and the other face having a complementary rib, 60 a clamping bolt for securing said plow to said arm concentric with respect to said ribs and extending substantially radial to the path of movement of said plow and adjustable means for retaining said plow in a predetermined position of adjustment about the axis of said clamping bolt.

5. In a grinding mill comprising a stationary grinding member and a plurality of co-operating grinding members rotatable 70 about a common central axis, a plow-supporting member also rotatable about said central axis, a plow, complementary faces upon said plow and said arm, one of said faces having a plurality of arcuate ribs and 75 the other face having a complementary rib, means for adjustably clamping said faces together including a bolt in one of said members concentric with its arcuate rib and extending substantially radial to the path of 80 movement of the plow and seated in a slot in the other member extending substantially in the direction of the axis of such member and adjustable means for retaining said plow in a predetermined position of adjustment 85 about the axis of said bolt.

6. In a centrifugal grinding mill comprising a grinding pan having a die, a central upright shaft, a quill shaft rotatable upon said upright shaft having a carrier 90 supporting a plurality of centrifugally operable grinding rolls, a spider carried by said quill shaft, a plow-supporting arm mounted upon said spider, means for clamping said plow-supporting arm upon said spider to 95 permit rotative adjustment about the axis of said arm, a plurality of parallel arcuate ribs upon the face of the lower portion of said arm concentric with respect to an axis substantially radial to the path of movement 100 of the plow, a plow comprising an upwardly extending member presenting a rib complementary to the ribs upon said plow-supporting arm and having a laterally offset end portion extending behind said plow-supporting arm, a bolt and slot connection between the upwardly extending member of said plow and said plow-supporting arm and a screw extending through the offset portion 105 of the upwardly extending member of said plow abutting against the rear face of said plow-supporting arm.

In testimony whereof, I have signed my name to this specification.

WILLIAM A. GIBSON.
